US0D1045820S

(12) **United States Design Patent** (10) **Patent No.:** **US D1,045,820 S**
(45) **Date of Patent:** **** Oct. 8, 2024**

(54) **MEDIA PLAYER DEVICE**

- (71) Applicant: **Sonos, Inc.**, Santa Barbara, CA (US)
(72) Inventors: **Youjin Nam**, Santa Barbara, CA (US);
                  Aki Laine, Santa Barbara, CA (US);
                  Edward Mitchell, Thousand Oaks, CA
                  (US)
(73) Assignee: **SONOS, INC.**, Goleta, CA (US)
(**) Term: **15 Years**
(21) Appl. No.: **29/915,415**
(22) Filed: **Oct. 30, 2023**

Related U.S. Application Data

- (63) Continuation of application No. 29/760,577, filed on Dec. 2, 2020, which is a continuation of application No. 29/757,435, filed on Nov. 5, 2020, which is a continuation of application No. 29/682,129, filed on Mar. 1, 2019, now Pat. No. Des. 906,279.

(57) **CLAIM**

The ornamental design for a media player device, as shown and described.

DESCRIPTION

FIG. 1 is a front elevation view of a media player device, according to our new design.

FIG. 2 is a rear elevation view thereof;

FIG. 3 is a left side view thereof.

FIG. 4 is a right side view thereof.

FIG. 5 is a top plan view thereof.

FIG. 6 is a bottom plan view thereof.

FIG. 7 is a perspective view thereof; and,

FIG. 8 is a second perspective view thereof.

The features shown in dash-dot broken lines form no part of the claimed design.

1 Claim, 7 Drawing Sheets
